UNITED STATES PATENT OFFICE.

RAY A. BROWN, OF ROCKFORD, ILLINOIS.

PORTABLE STEREOTYPE-CASTING BOX.

Application filed February 12, 1925. Serial No. 8,667.

My invention relates to stereotype casting boxes and more particularly to a small portable casting box for making stereotype castings, either single or double column widths or smaller castings, such as are adapted for use in newspaper offices, especially for last minute news or emergency purposes.

The invention provides a novel casting box including a pair of plates or mold sections having novel means for producing a single or double column and novel means for holding the plates in position for use and adapted to cooperate with gauge blocks by which the different widths of columns may be cast.

Other objects and advantages will be apparent from the following description taken in connection with the accompanying drawings in which:

Figure 1 is a plan view of my novel casting box;

Fig. 2 is an end view of the device;

Fig. 3 is an enlarged sectional view taken through the gauge blocks and showing the latter in position for casting a stereotype of double column width;

Fig. 4 is a view similar to Fig. 3 but showing one of the gauge blocks adjusted to produce a stereotype of single column width; and

Fig. 5 is a fragmentary transverse sectional view showing the assembly of the plates or sections of the casting box and the manner of securing the stationary gauge block in position.

Referring to the drawings in detail, in which like reference characters designate corresponding parts throughout the several views, my novel stereotype casting box consists of an upper plate or section 6 corresponding to the cover of an ordinary casting box as heretofore constructed, and 7 designates the lower plate or mold section. These plates are provided with reinforcing ribs or fins 8 adapted to produce the necessary strength and yet a lightweight structure. One end of each plate is provided with pivot ears 9 and 10, the pivot ears of one section interfitting the pivot ears of the other section and connected by a pin 11

whereby the plates or sections may have hinge or swinging movement toward and away from each other in opening and closing the box. A lug 12 is provided on one of the ears such as the ear 10, and projects laterally therefrom toward the outside for engagement by a stop shoulder 13 formed upon the periphery of the adjacent outer ear 9, thus limiting the opening or separation of the plates and serving to support the plate 6 in an upright position upon the plate 7 when the box is open.

At the free ends of the plates handles 14 are provided, said handles cooperating to be jointly grasped for retaining the plates toward each other. The plate 7 is further provided with an apertured hasp 15 projecting rigidly across the ends of the plates and beyond the top face of the plate 6, the aperture 16 thereof being adapted to receive a wedge shaped lug 17 projecting forwardly upon the intermediate portion of a lever 18 which is pivoted at 19 at one corner of the top plate 6. The handle portion of the lever 18 projects beyond the opposite end of the plate 6 and is limited in its movement rearwardly to disengage the lug 17 from the aperture or eye 16 by contact with a projection 18' extending up from the adjacent end of the plate 6. The tapered lug 17 cooperating with the eye 16 in the hasp 15 provides the necessary pressure between the plates to retain the cast or molded stereotype in form, and yet permits the quick removal and release thereof even while hot, without permitting adherence between the parts such as would render the product useless.

In practice, the plates are normally spaced apart and at the hinged ends thereof a stationary gauge block or bar 20 is provided, being secured to the plate 7 in the preferred construction by screws or the like indicated at 21 and having their heads 22 embedded in the top surface of the gauge block 20 as clearly indicated in Fig. 5 of the drawings.

The gauge block 20 as will be noted from Figs. 3 and 4 of the drawings, terminates a spaced distance from one edge of the plate 7, to accommodate the thickness of a right angular gauge block 23 which extends along

the adjacent edge and also along the edge opposite the edge along which the gauge block 20 is provided, and contiguous to the open end of the casting box. The gauge block 23 may be formed as an integral structure or a pair of bars suitably connected as indicated at 24. This gauge block 23 is adjustable between the plates and when clamped adjacent to the free ends thereof as shown in Fig. 3, a stereotype of two column width may be cast. By adjusting the angular or movable gauging block 23, a column of any suitable width may be produced and, as illustrated in Fig. 4 of the drawings, the gauge block is adjusted to produce a stereotype of single column width. In accomplishing this, the portion of the gauge block which is parallel to the gauge block 20 is adjusted toward the latter and the bottom portion designated at 25, is adjusted through the opening or recess provided where the block 20 terminates short of the adjacent edges of the plates 6 and 7, between which the gauge blocks are positioned. A straight-edge guide 26 secured to the bottom plate 7 provides an accurate guide for the gauge block 23 so as to keep its upright portion parallel with the gauge block 20.

In the use of the device, a matrix 27 is disposed in position against plate 7 and then the gauge blocks are positioned between the plates and the latter are brought together by the handles 14, after which the tapered lug or wedge 17 is forced into the eye 16 of the lug 15 through the instrumentality of the handle 18 swinging away from the projection 18'. The device is then tilted on edge as shown in Figs. 3 and 4 and the molten metal poured into the box for casting a stereotype of the desired width. It will be noted that the matrix underlies the gauge blocks 20 and 23 as shown in Figs. 2 and 5. This produces sharp edges on the matrix and eliminates the usual fin edges and trimming thereof, heretofore necessary.

A device of the construction described is especially desirable for newspaper offices for last minute news or emergency purposes and being comparatively small and light in weight, can be easily handled or transported from place to place. The adjustment of the gauge blocks can be conveniently accomplished so that a column of the desired width may be produced at will. The device is also simple in construction and capable of economical production. It may also be pointed out that by reason of the projection 18', when the stereotype has been cast, the handle 18 is swung into engagement with the projection to disengage the wedge 17 from the lug 15 and the handle is therefore prevented from swinging down where it is apt to render the device inconvenient to handle or where it is not accessible for use.

I claim:

1. A portable casting box for making stereotype castings and the like comprising a pair of hinged plate sections, a spacing member fixed to one of said plates at one end of the latter, a guide on said plate in spaced relation to one end of said member and at right angles thereto, an adjustable L-shaped spacing member movable along said guide with the one leg thereof operating between said guide and the end of the other member whereby to vary the width between the other leg thereof and said member, and means for clamping said plates together against said members.

2. In a portable casting box comprising a pair of plate sections arranged to be clamped together, a spacing member stationarily fixed on one of said plates but arranged to have limited vertical movement relative thereto to permit the introduction therebeneath on said plate of a matrix, a stationary guide on said plate in spaced relation with one end of said member and at right angles thereto, and an adjustable L-shaped spacing member having the one leg thereof movable along said guide in the space between said guide and the end of the other member arranged upon adjustment to vary the width of the casting molded by varying the width between the other leg of said adjustable member and said first member.

3. A portable stereotype casting box comprising a pair of hinged plate sections, gauge blocks therebetween, means for holding said plates in clamping engagement with the gauge blocks, and means in the hinged connection between said plates for limiting the separation thereof.

4. A portable stereotype casting box comprising a pair of hinged plate sections, gauge blocks between said plates, means for holding the plates in clamping engagement with said blocks, and handle portions on said plates extending at an angle to the planes thereof toward one another whereby in the closed condition of the plates to have the gripping portions thereof lie alongside one another and provide a convenient carrying handle.

5. In a stereotype casting box, a pair of hinged sections, gauge blocks arranged therebetween, and means for holding said sections in clamping engagement with said blocks comprising a lug projecting from the end of one section across and beyond the end of the other section and having an eye in the outer end thereof, and a handle pivoted on the last mentioned section near the last mentioned end thereof having a wedging lug extending from the side thereof to enter the eye of the lug on the other section to clamp said plates together.

6. In a stereotype casting box, a pair of

hinged sections, gauge blocks arranged therebetween and means for holding said sections in clamping engagement with said blocks comprising a lug projecting from the end of one section across and beyond the end of the other section and having an eye in the outer end thereof, and a handle pivoted on the last mentioned section near the last men-

tioned end thereof having a wedging lug extending from the side thereof to enter the 10 eye of the lug on the other section to clamp said plates together, and a stop behind said handle on the same member therewith arranged to limit the swinging movement of said handle from operative position.

RAY A. BROWN.
